UNITED STATES PATENT OFFICE.

FREDERICK W. COYNE, OF TORONTO, CANADA.

DESIGN FOR A CAMPAIGN PIN OR BUTTON.

SPECIFICATION forming part of Design No. 26,234, dated November 3, 1896.

Application filed September 8, 1896. Serial No. 605,200. Term of patent 3½ years.

To all whom it may concern:

Be it known that I, FREDERICK W. COYNE, a subject of the Queen of Great Britain, and a resident of the city of Toronto, in the county of York and Province of Ontario, Canada, have invented a new and original Design for Buttons, of which the following is a specification, reference being had to the accompanying drawings, illustrating the same.

Figure 1 in the drawings illustrates my design in perspective, and Fig. 2 is a similar view with the lid or cover of the button-head removed.

The head A of the button is of rectangular or box-like form, with plane ends and sides and a cover B.

The front side of the box A contains a suit-

able panel D for any desired words or ornamentation, and the rear side of the box is provided with a pin L and a pendent cord I. 20

The characteristic feature of my design is a box-like receptacle having a lid or cover and provided with a pin and a pendent cord and adapted for use as a campaign button or pin. 25

I claim—

The design for a button or campaign-pin as herein shown and described.

Toronto, August 12, A. D. 1896.

F. W. COYNE.

In presence of—

M. A. WESTWOOD,
C. H. RICHES.
